UNITED STATES PATENT OFFICE

CARL G. A. SCHMIDT, JR., OF KENNETT SQUARE, PENNSYLVANIA, ASSIGNOR TO AMERICAN ROAD MACHINERY COMPANY, INC., OF KENNETT SQUARE, PENNSYLVANIA, A CORPORATION OF DELAWARE

ROCK CRUSHER

Application filed August 31, 1928. Serial No. 388,670.

This invention relates to a rock crusher and has more particular reference to the type of device having a stationary jaw and a movable jaw to which latter there is imparted a reciprocating rocking movement in order to crush rock or other material passing between the jaws.

Heretofore in mechanisms of this character, in which the movable jaw was hung upon a shaft provided with eccentrics, it was found that breakage of the shaft occurred at times, particularly between the bearings supporting the shaft in the frame and the bearings supporting the movable jaw upon the eccentric.

It is the primary object of this invention to overcome this difficulty by an arrangement of bearings whereby the shaft is rendered free to flex so that a distribution of the stresses occurs without imposing upon any part of the shaft a concentrated breaking stress. The improved construction forming the subject matter of this invention makes possible minimum distance between the bearings with proportionate increases of the safe working load; or, in other words, increases the factor of safety for the same size shaft.

It is a further object of the present invention to provide automatic means for preventing breaking of the working parts of the mechanism in case the movable jaw is jammed by the introduction of hard material such as iron bolts or tools or the like.

Another object relates to the provision of means for easy and quick adjustment whereby different grades of fineness may be produced in the crushed materials, the adjustment also serving to permit taking up of the parts as wear on the jaws proceeds.

Other more detailed objects relate to a construction whereby stresses are properly distributed so as to minimize breakage, and, conversely, to obtain the maximum strength for any given shaft. Among these provi-

sions are constructions whereby shear on bolts is prevented during the operation of the mechanism.

Further objects will become apparent when the following description is read in conjunction with the accompanying drawings, in which:

Fig. 1 is a vertical sectional view showing the operating parts of the mechanism;

Fig. 2 is a transverse section through the mechanism;

Fig. 3 is an enlarged section on line 3—3 of Fig. 2;

Fig. 4 is a diagrammatic view showing the effect of stresses upon the construction heretofore used; and

Fig. 5 is a similar view showing the effect of stresses upon the improved machine.

The crusher, which is supported upon a suitable base during operation, includes a rigid frame preferably formed by two side plates 2 of rolled steel to provide a somewhat flexible construction, which plates are transversely connected by heavy castings in a manner which will later be described. A cover plate 4 serves to protect the moving parts from the charge of stone or materials entering the jaws. This cover plate 4 is preferably secured by means of U-bolts which embrace cross members extending between the opposite plates 2. These cross members preferably consist of tie bolts connecting the two plates, pipes surrounding the tie bolts between the plates to provide their proper spacing.

Bearing housings 6 are inset, as indicated at 8, within apertures in the upper ends of plates 2, the housing being provided with flanges which are bolted to the plates. By reason of the inset arrangement, any stresses imparted to the bearings are taken up directly by the plates, so that destructive shearing stresses are not imparted to the bolts securing the housings to the frame. Within each housing 6 is located a self-

On each outer end of the shaft is secured a bushing 20 held in place by means of a nut 22. In the case of the left hand bushing, shown in Fig. 1, a spacer is interposed between the nut and the bushing. This may be replaced by a sprocket wheel for driving other equipment. Each of the bushings is provided with an outer flange 24 to which a flywheel 26 is secured by means of a plurality of bolts 28 passing through the hub of the flywheel and the flange 24. These bolts 28, of which three may be used in connecting each flywheel, are made of brass or some other non-corrosive material, so that 20 in case jamming of the movable jaw occurs, the heavy flywheel will shear off the bolts and continue to revolve without imposing destructive stresses upon the eccentric shaft, the bearings, or the movable jaw.

40 In case a jamming of this sort occurs and the flywheel continues to revolve on the bushings 20, it might be possible that the friction would cause a binding of the flywheels with the bushings so as to destroy the effectiveness of the shearing pins and with a resultant destruction of the operating parts. To minimize the heating effect in case a flywheel so revolves on the bushing, each of the bushings is annularly grooved, 45 as indicated at 32, in order to reduce the friction surface. This is, each flywheel will bear only on the outer ends of the surface of its corresponding bushing, the annular space being packed with grease. In order to prevent the flywheel, during such rotation, from moving inwardly and destroying the bearing housing or its cover 18, a washer 30 is interposed between the bushing 20 and a shoulder on the shaft. This 50 washer extends radially outwardly beyond the bushing, so as to prevent inward movement of the flywheel.

In the present embodiment of the invention, the shaft 12 is turned, with the formation of two eccentrics 34, although it will

be understood that separate eccentrics may be mounted on the shaft. On each of these eccentrics is mounted the inner race of a ball or roller bearing 36 of the self-aligning type similar to 10. The inner race is shrunk upon the eccentric and held laterally by means of a nut and lock washer arrangement 38. The outer bearing races support the outer end 40 of the movable jaw 42. As will be seen from Fig. 1, the upper portion 40 of the jaw is made hollow and is provided with covers 44 at its ends so that a lubricant chamber is produced into which grease may be forced under pressure to provide efficient lubrication for the bearings.

70 Tension rods 46 are pivoted to the opposite sides of the lower end of the movable jaw and pass through openings in a transverse portion of the frame, as indicated in Fig. 2. Each rod is provided at its outer end with a collar 48 against which abuts one end of a compression spring 50 which, at its lower end, reacts against the portion of the frame adjacent the opening. The springs 50 serve to hold the jaw as indicated in Fig. 2, against the toggle 52, of which one cylindrical end bears in a wear plate on the jaw and of which the other cylindrical end bears in a wear plate 54 carried by a block member 56. The block member may be provided, as indicated most clearly in Fig. 3, with tapered surfaces which engage wedges 58 arranged to be drawn together or forced apart by means of a shaft 60 threaded oppositely through the wedges and provided at its outer end with a squared end 62' adapted to be moved by means of a suitable tool or wrench. It will be noted that wear plate 54 is secured to block 56 by means of a dowel pin or the like, which block is suitably guided for inward or outward movement as the wedges are forced apart or drawn together. The transverse frame member which carries these parts is provided with tongues at its 90 opposite ends seated in grooves 62 in the side plates 2 and is bolted to the side plates. By reason of the tongue and groove connection, the stresses are taken from the bolts and applied directly from the transverse 95 frame member to the side plates. Shearing of the bolts is thus avoided.

100 A die 64 which provides a wearing surface for the crushing of the rock is clamped in the movable jaw 42, being fixedly held therein by means of wedges 55 engaging one end while the other end engages an undercut recess in the jaw.

105 The fixed jaw 68, which extends between the side plates and is provided with tongues 110 engaging within grooves in the side plates in a manner similar to that described in connection with grooves 62, carries a stationary die 70 clamped to the fixed jaw by means of clamping plates 72. Cheek plates 115

74 are secured to the inner walls of side plates 2 in order to take the wear of the stone passing between the jaws, these plates being formed of hardened steel.

5 The operation of the mechanism will, in a general way, be obvious from the above description. As the shaft revolves the operating face of the die 64 has imparted thereto a kind of oval motion so as to serve to crush rock introduced between the two dies and also tend to pass it through the dies.

10 Heretofore in prior constructions, the bearings which have been used to mount the shaft in the side walls of the frame have been of a self-aligning construction. 15 On the other hand, the bearings which mount the movable jaw upon the eccentrics have been of the ordinary non-self-aligning type resulting in a rigid assembly 20 from end to end of the jaw. The effect of the prior construction is illustrated in Fig. 4, in which the ordinary bearings mounting the movable jaw are indicated at *a*, the self-aligning bearings mounting the 25 shaft within the frame at *b* and the shaft itself at *d*. The center line of the outer bearings is indicated at *c-c*. As the shaft revolves, and due to the crushing stresses, the shaft will be distorted more or less, deflecting it out of the center line *c-c*, as indicated by the position of the shaft in this figure. Because of the fact that the bearings *a-a* are of the ordinary type and are both rigidly housed within the movable jaw, 30 it is impossible for the portion of the shaft between these bearings to bend. In other words, the axis of the bearings will remain in alignment.

35 Consequently, as flexure of the shaft must take place because of the stresses imparted to the movable jaw, all of the flexure of the shaft must necessarily take place at the ends between bearings *a* and bearings *b*, as indicated in the figure. Inasmuch as this distortion is of a considerable amount, being 40 proportional to the stresses, the radii of curvature of the end portions of the shaft are relatively small, as indicated by the converging dash lines in the figure.

45 On the other hand, in the improved construction incorporating all self-aligning bearings, the action of which is diagrammatically illustrated in Fig. 5, in which the self-aligning supporting bearings for the movable jaw are indicated at *m* and the shaft bearings at *n*, the shaft itself being indicated at *o*, the shaft is free to flex with a resultant very large radius of curvature so that the stresses are minimized and distributed throughout the shaft. As a result, 50 greater strength is obtained in the same shaft without danger of breaking between the bearings. Also, it will be quite obvious that if the whole shaft may flex freely, the bearings *m* and *n*, being both self-aligning,

may be brought very close together with the resultant increase in the strength of the shaft.

55 It will be clear that the constructions shown in Figs. 4 and 5 are merely diagrammatic, that is, no attempt has been made to indicate the eccentricity of the portions of the shaft supporting the movable jaw.

60 From the above description it will be seen that the stresses in the driving shaft have been minimized by use of self-aligning bearings throughout. It will also be seen that the stresses upon the securing bolts for the frame have been minimized so as to prevent shearing thereof. The pins securing the flywheels to the shaft prevent destruction of the machine in case of jamming. There is also provided an adjustment for wear between the jaws and for the production of different sizes of crushed material.

65 What I claim and desire to protect by Letters Patent is:

70 1. A crusher comprising a frame, a plurality of jaws, one of said jaws being movable relatively to the other to crush materials therebetween, a driving shaft, self-aligning bearings mounting the shaft in the frame, an eccentric on the shaft, and a self-aligning bearing surrounding the eccentric and supporting the said movable jaw.

75 2. A crusher comprising a frame, a plurality of jaws, one of said jaws being movable relatively to the other to crush materials therebetween, a driving shaft, self-aligning anti-friction bearings mounting the shaft in the frame, eccentrics on the shaft, and self-aligning anti-friction bearings surrounding the eccentrics and supporting the said movable jaw.

80 3. A crusher comprising a frame, a plurality of jaws, one of said jaws being movable relatively to the other to crush materials therebetween, a driving shaft, self-aligning bearings mounting the shaft in the frame, eccentrics on the shaft, self-aligning 85 bearings surrounding the eccentrics and supporting the upper end of the movable jaw, and means for guiding the lower end of the movable jaw.

85 4. A crusher comprising a frame, a plurality of jaws, one of said jaws being movable relatively to the other to crush materials therebetween, a driving shaft, self-aligning anti-friction bearings mounting the shaft in the frame, eccentrics on the shaft, self-aligning anti-friction bearings surrounding the eccentrics and supporting the upper end of the movable jaw, and means for guiding the lower end of the movable 90 jaw.

95 5. A crusher comprising a frame, a plurality of jaws, one of said jaws being movable relatively to the other to crush materials therebetween, a driving shaft, self-aligning bearings mounting the shaft in the 100

frame, eccentrics on the shaft, self-aligning bearings surrounding the eccentrics and supporting the upper end of the movable jaw, and means for guiding the lower end of the movable jaw in an arc.

6. A crusher comprising a frame, a plurality of jaws, one of said jaws being movable relatively to the other to crush materials therebetween, a driving shaft, self-aligning bearings mounting the shaft in the frame, eccentrics on the shaft, self-aligning bearings surrounding the eccentrics and supporting the upper end of the movable jaw,

10 and adjustable means for guiding the lower 15 end of the movable jaw.

7. A crusher comprising a frame, a plurality of jaws, one of said jaws being movable relatively to the other to crush materials therebetween, a driving shaft, bearings mounting the shaft in the frame, eccentrics on the shaft, and bearings surrounding the eccentrics and communicating with a lubricant chamber in the movable jaw.

8. A crusher comprising a frame, a plurality of jaws, one of said jaws being movable relatively to the other to crush materials therebetween, a driving shaft, bearings mounting the shaft in the frame, eccentrics on the shaft, and anti-friction bearings surrounding the eccentrics and communicating with a lubricant chamber in the movable jaw.

9. A crusher comprising a frame, a plurality of jaws, one of said jaws being movable relatively to the other to crush materials therebetween, a driving shaft, self-aligning bearings mounting the shaft in the frame, eccentrics on the shaft, and self-aligning bearings surrounding the eccentrics and communicating with a lubricant chamber in the movable jaw.

10. A crusher comprising a frame, a plurality of jaws, one of said jaws being movable relatively to the other to crush materials therebetween, a driving shaft, self-aligning anti-friction bearings mounting the shaft in the frame, eccentrics on the shaft, and self-aligning anti-friction bearings surrounding the eccentrics and communicating with a lubricant chamber in the movable jaw.

11. A crusher comprising a frame having side plates, a plurality of jaws, one of said jaws being movable relatively to the other to crush materials therebetween, a driving shaft, bearings mounting the shaft in the frame, said bearings being located in openings in the side plates whereby the plates receiving directly stresses on the bearings, eccentrics on the shaft, and bearings surrounding the eccentrics and located within a lubricant chamber in the movable jaw.

12. A crusher comprising a frame having side plates, a plurality of jaws, one of said 65 jaws being movable relatively to the other

to crush materials therebetween, a driving shaft, bearings mounting the shaft in the frame, said self-aligning bearings being located in openings in the side plates whereby the plates receive directly stresses on the 70 bearings, eccentrics on the shaft, and self-aligning bearings surrounding the eccentrics and located within a lubricant chamber in the movable jaw.

In testimony of which invention, I have 75 hereunto set my hand, at Kennett Square, Pa., on this 28th day of August, 1929.

CARL G. A. SCHMIDT, JR.
